UNITED STATES PATENT OFFICE

162,207

PORTABLE GUNRACK

Michael W. Mettenleiter, New York, N. Y.

Application March 18, 1949, Serial No. 1,468

Term of patent 7 years

(Cl. D80—9)

To all whom it may concern:

Be it known that I, Michael W. Mettenleiter, a citizen of the United States of America, residing in New York city, county of New York, and State of New York, have invented a new, original, and ornamental Design for a Portable Gunrack, of which the following is a specification, reference being had to the accompanying drawing, forming part thereof, wherein,

Figure 1 is a front perspective view of a portable gunrack showing my new design in open position.

Figure 2 is a side elevational view.

Figure 3 is a front elevational view.

Figure 4 is a view similar to Figure 3, showing the portable gunrack in semi-closed position.

Figure 5 is a front perspective view of the portable gunrack shown in Figure 1, in closed position.

I claim:

The ornamental design for a portable gunrack, substantially as shown.

MICHAEL W. METTENLEITER.
